UNITED STATES PATENT OFFICE.

CHARLES B. JAHNKE, OF BELOIT, WISCONSIN, ASSIGNOR TO FAIRBANKS, MORSE & CO., OF CHICAGO, ILLINOIS, A CORPORATION OF ILLINOIS.

GOVERNOR CONTROL FOR INTERNAL-COMBUSTION ENGINES.

Application filed October 9, 1924. Serial No. 742,631.

My invention relates to improvements in governor control for internal combustion engines and more particularly to improvements in that type of governor control 5 known as the hit-and-miss type.

The object of my invention is to provide a means for controlling the admission of fuel and the ignition thereof in an internal combustion engine which is simple to manufacture, easy to assemble and positive in its action.

Although my invention consists largely in the construction and arrangement of parts hereinafter described and particularly 15 pointed out in the claims, yet I do not limit my invention to the precise form, construction or arrangement of parts shown or the several parts thereof, inasmuch as various alterations may be made without changing 20 the scope of my invention.

In the drawings Fig. 1 is an end view of a preferred form of my invention as mounted 25 on an engine, partially in section; Fig. 2 is a detail drawing of a pivoted member preferably employed in my invention; Fig. 3 is an elevational view partially in section, 30 of an internal combustion engine making use of a preferred form of my invention; and Fig. 4 is a view partially in section of a fragment of the valve rod and contacting mechanism.

Referring by numerals to the drawings, the member 5 is preferably pivoted on the bracket or support 6 at 7. The support 6 is pivoted at 8 to bracket 9 which is preferably mounted on the engine as shown. Attached rigidly to the support 6 may be placed a regulator handle 10 preferably made out of spring steel and carrying a 40 raised edge 11. The edge 11 may be made to engage with depressions 12 in a portion of the bracket 9. These depressions serve to hold the handle 10 and with it the carrier 6, in any desired position. One end 13 of member 5 is adapted to make contact with the end of the governor spindle 14. This spindle is acted upon by the governor weights 15 through the pieces 15 against the action of spring 23, and the tendency is for 45 the governor to push the spindle 14 outwards as the speed of the engine is increased. The governor weights 15 are pivoted onto the hollow shaft 20 which is driven by the half-time gear 21 through the pinion 22. The 50 member 5 is adapted at its end 16 to engage

with a shoulder 17 on valve rod 18. A spring 19 is preferably used to hold the end 13 of member 5 in contact with the spindle 14. When the operating end 16 of the member 5 is pushed into contact with valve rod 18 by the action of the governor spindle 14, it engages with shoulder 17 and thereby serves to keep the rod 18 from returning to its normal or closed position. This action holds the exhaust valve (not shown) open and thus prevents the engine from sucking in a mixture. This action will continue until the speed of the engine has fallen sufficiently so that the end 16 of the member 5 is released from engagement with shoulder 17.

The support 6, preferably being pivoted to the bracket 9 at 8, permits the fulcrum 7 of member 5 to be moved towards or away from the governor spindle 14 by means of the handle 10 and, since the position of the spindle 14 is different for different speeds of the engine, this affords an efficient means for regulating the speed of the engine.

The valve rod 18 preferably has attached to it the collar 24 which serves as a contact member for my timing device as described in my application filed October 9, 1924, Serial Number 742,630. This collar makes periodical electrical contact with plate 25, thereby closing the low tension circuit (not shown) of the ignition system. Plate 25 is preferably carried by the valve rod supporting member 26 and is insulated therefrom by piece 27. At 28 is shown the roller which acts in conjunction with cam 29 to operate the valve rod 18. It is evident that when the end 16 of the pivoted member 5 has been interposed behind shoulder 17 of the valve rod 18, through the action of the governor weights 15 and spindle 14, the result will be to prevent any electrical contact between the collar 24 and plate 25, thereby preventing any ignition taking place in the cylinder and at the same time holding the exhaust valve open.

I claim:

1. In an internal combustion engine, in combination with a valve, a push-rod therefor, a pivoted lever adapted to control said valve, an adjustable fulcrum for said lever, means for imparting an arcuate movement to said fulcrum, and a governor controlling said member, a portion of said pivoted member being adapted for operative connection 105

110

directly with the said governor, and another portion thereof being adapted as an abutment for said push-rod.

2. In an internal combustion engine, in combination with a valve, a reciprocating valve rod, an adjustable bracket, a pivoted member mounted on said bracket and adapted to control said valve, said bracket being arcuately movable, and adapted as a fulcrum for said pivoted member, and a governor controlling said member, and in direct operative association therewith.

3. In an internal combustion engine, in combination with an exhaust valve, a reciprocating valve rod, a pivoted member adapted to control said exhaust valve, an angularly adjustable fulcrum for said member, means for swinging said fulcrum about a pivot, a governor controlling said member, and in direct operative association therewith.

4. In an internal combustion engine, in combination with an exhaust valve and a push-rod therefor, a bracket, a pivoted lever, having a fulcrum on said bracket and adapted to prevent the closing of said exhaust valve, manually movable means for imparting a rocking movement to said bracket and fulcrum, and a governor controlling said lever, said lever constituting an operative connection between said governor and said valve rod.

5. In an internal combustion engine, the combination of a valve, a reciprocating valve rod, a pivoted member adapted to be moved across said rod to hold said valve in open position, a governor controlling the pivoted member, a support for the pivoted member, and means on the support for arcuately moving the pivot of said member, and adapted as a speed adjustment for the engine.

6. In combination with a reciprocating

valve rod and a governor, a structure comprising an angularly movable yoke, a lever pivotally fulcrumed in said yoke and adapted to bear on the valve rod through the direct action of the governor, and means for rocking said yoke and fulcrum, adapted to effect a speed control of the engine.

7. In an internal combustion engine, the combination of a governor, a valve push-rod, and an intermediate pivoted lever adapted to be engaged by said governor and to move across the path of travel of said rod, a fulcrum therefor, adapted to be swung about a fixed center, whereby the governor control of said valve rod may be varied.

8. In an internal combustion engine, in combination with a reciprocating valve rod, a lever adapted to bear on the rod and to control the action thereof, a yoke adapted as a fulcrum for said lever, pivoted speed-control means adapted to impart a rocking movement to said yoke, a governor mechanism comprising a hollow shaft and a spring-pressed spindle adapted to move relatively to each other, governor weights carried by said shaft, said spindle adapted to operate said lever through the governor weights.

9. In an internal combustion engine, in combination with a reciprocating valve rod and a detent lever adapted to bear thereon, a governor mechanism comprising a hollow shaft, governor weights carried by said shaft, a spring-pressed spindle adapted to operate through said shaft upon said lever under the action of said governor weights, a swingable yoke comprising a fulcrum for the lever, and means on the yoke for adjusting the position of the fulcrum of the pivoted member with respect to the spindle.

CHARLES B. JAHNKE.
